UNITED STATES PATENT OFFICE

2,438,783

CABINET WITH COMPARTMENTS HAVING
INTERCONNECTED LOCKING MEANS

Charles H. Kraft, Kansas City, Mo.

Application May 16, 1944, Serial No. 535,887

3 Claims. (Cl. 312—106)

1

This invention relates to a unitary structure comprising a clothes compartment and one or more series of lockers for holding small articles such as shoes, caps and the like. An important feature of the invention resides in interlocking means for securing garments in the compartment against removal by unauthorized persons, also for locking doors with which the lockers are provided to prevent unauthorized removal of articles therefrom.

Other features will hereinafter appear and in order that the invention may be fully understood reference will now be had to the accompanying drawing, in which—

Fig. 1 is a front elevation of a cabinet embodying my invention.

Fig. 2 is a vertical sectional view of the cabinet on line 2—2 of Fig. 1.

Fig. 3 is an enlarged fragmentary front elevation showing locking means forming important features of the invention.

Fig. 4 is a fragmentary vertical section taken on line 4—4 of Fig. 3.

Fig. 5 is a detail of locking means.

Fig. 6 is a detail of a garment hanger and associated parts.

In carrying out the invention I provide a cabinet 2, comprising a compartment 4 and two superposed series of lockers 6 and 7, respectively. The uppermost series of lockers 7 may be dispensed with and the front side of the compartment 4 may be provided with a closure such, for example, as a curtain or hinged doors, not shown. Entrance to the lockers 6 and 7 is controlled by associated doors 8 and 9, preferably connected at their upper ends to frame portions 10 and 11 of the lockers by hinges 12 and 13, so that they will automatically swing downward to closed position after being opened by knobs 14 and 15 secured to the lower portion of the doors 8 and 9, respectively.

The upper part of the compartment 4 is provided with a horizontal rod firmly secured at its ends to the oppositely-disposed side walls 18 of the compartment. The rear portion of the compartment 4 and the lockers 6 and 7 are closed by a wall which cooperates with the side walls 18 in excluding dust from garments in the compartment 4 and articles in the lockers 6 and 7. The rod 16 is provided with a plurality of suspension members 20, each having an eye 22 at its upper end whereby it is slidably and permanently mounted upon the rod 16. Each suspension member 20 is preferably in the form of a hook adapted to removably receive an eye 24 at the upper end of an associated garment hanger 26, permanently con-

2

nected to the suspension member by means of a short flexible member 28. Each flexible member 28 is preferably in the form of a chain permanently connected by end links 30 and 31 to an associated hook 20 and garment hanger 26, respectively. One end of each hook 20 is provided with a lug 32 to prevent removal of the associated link 30. The chains 28 prevent the garment hangers 26 from being carried off, but permit them to be removed from the compartment 4 far enough so that garments can be easily applied to or removed from said garment hangers.

Suitable means are provided for preventing garments from being carried off by an unauthorized person. Such means, in the present instance, comprises a plurality of flexible members 34 and means for locking the same. Each flexible member 34 is longer than each chain 28 and is preferably in the form of a chain having one end permanently secured to either an associated garment hanger 26 or a hook 36, which latter is permanently connected to the former by an eye 38. Securing a garment with the associated chain 34 is accomplished by passing the free end of the chain through the lapel, button-hole or one sleeve of the garment and then hooking the end link 40 over the prong 42 of a short bolt 44 slidably connected, as by a pin-and-slot 46, to a bracket 48 fixed to the underside of a frame member 50 at the upper portion of the compartment 4.

The upper end of the bolt 44 extends through an aperture 52 in the floor 54 of an associated locker 6 of the lower series and when the bolt is pushed upwardly its upper end enters a keeper 56 fixed to the inner lower portion of the associated door 8 of said locker. Thus the door 8 is simultaneously locked with the locking of the link 40. The bolt 44 and the bracket 48 have holes 58 and 60, respectively, adapted to register when the bolt 44 is pushed upward into engagement with the keeper 56, so that the hasp 62 of a padlock 64 may be placed through the registering holes and thereby secure the bolt in locked position. When the bolt 44 is pushed upward into engagement with the keeper 56, as stated, the upper end of the prong 42 enters a recess 66 in the frame member 50 and thus prevents removal of the link 40.

The hooks 36 may be utilized for supporting hats, belts and other articles.

Each door 9 of the upper series of lockers 7 is adapted to be locked in closed position by an associated relatively long bolt 68 slidably arranged beside the shorter bolt 44 on the bracket 48 to which latter the longer bolt 68 is connected by a pin-and-slot 70. The long bolt 68 extends up-

wardly through apertures 72 and 74, Fig. 3, in the floor 54 of the lower compartment 6 and the floor 75 of the superposed compartment 7, respectively, and is adapted to engage a keeper 78, Figs. 2, 3 and 4, fixed to the inner side of the associated upper door 9. The long bolt 68 is slidably mounted in guides 80, Figs. 2 and 4, secured in the lower compartment 6 to the frame portion 82 of the compartment 4 and said bolt 68 is provided at its lower portion with a prong 84, the upper end of which is adapted to enter a recess 86 in the lower frame member 50 and thus lock the end link 40 of an associated chain 34 at the same time that said upper door 9 is locked by the long bolt 68. The major portion of the bolt 68 within the lower locker 6 is bent toward frame 82, so as to be out of the way when articles are being placed in or removed from the locker.

Each bracket 48 and the lower portion of each long bolt 68 are provided with apertures 88 and 90, respectively, which are adapted to register and receive the hasp 92 of a padlock 94, when the long bolt 68 is pushed upward into engagement with the associated keeper 78.

From the foregoing description taken in connection with the accompanying drawing, it will be understood that the link 40 of any long chain 34 and the associated lower door 8 can be simultaneously locked with one respective short bolt 44 and padlock 64. Also that any link 40 and the upper associated door 9 can be simultaneously locked with one respective long bolt 68 and padlock 94, thereby avoiding the necessity of providing separate bolts and padlocks for each link 40 and door 9.

While I have shown and described certain preferred embodiments of my invention I reserve all rights to such changes and modifications thereof as properly fall within the scope of the invention as claimed.

Having thus described my invention, what I claim and desire to secure by Letters Patent is:

1. In combination, a compartment, a locker superposed upon the compartment and provided with a door for closing the locker, means including a flexible element permanently secured at one end in the compartment, the other end being free to pass through an opening in an article, a bolt extending from the compartment into the locker through an aperture in the bottom of the latter and provided with means for securing the free end of the flexible element to the bottom of the locker, a member fixed to the bottom of the locker and upon which the bolt is slidably mounted, a

keeper fixed to the inner side of the locker door to receive the upper end of the bolt and cooperate therewith in locking the door, and member for locking the bolt to said member upon which it is slidably mounted.

2. In combination, a combined compartment and locker, said locker being superposed on the compartment, a door for closing the locker, a garment hanger in the compartment, means in the compartment for supporting the garment hanger, a flexible member having a free end adapted to be passed through the button hole or sleeve of a garment and another end permanently connected to the garment hanger, a keeper fixed to the inside of the door, a bolt extending from the compartment into the locker through an aperture in the bottom of the latter and adapted to be moved into engagement with said keeper to lock the door in closed position, a prong fixed to said bolt and adapted to secure the free end of the flexible member to the bottom of the locker, a member fixed to the bottom of the locker and upon which the bolt is operably mounted, and means for locking the bolt to said member.

3. In combination, a compartment, a plurality of lower lockers superimposed upon the compartment, a plurality of upper lockers superimposed upon the lower lockers, a door for closing each locker, a keeper fixed to the inner side of each door, bolts extending upward from the compartment through apertures in the bottoms of the lockers and adapted to engage the keepers and lock the respective doors in closed position, brackets fixed to the bottom of the lower lockers and upon which the bolts are operably mounted, each associated bracket and bolt having apertures which register when the bolt is in engagement with its respective keeper, and a lock for each bolt having a hasp adapted to pass through the registering apertures and lock the bolt to the bracket.
